[57] CLAIM

The ornamental design for a mirror toy, substantially as shown.

DESCRIPTION

FIG. 1 is a perspective view of a mirror toy showing our new design;

FIG. 2 is a right side elevational view thereof;

FIG. 3 is a top plan view thereof;

FIG. 4 is a bottom plan view thereof;

FIG. 5 is a reduced size rear elevational view thereof; and

FIG. 6 is a reduced size perspective view, taken generally from the rear, and showing a portion of the mirror toy illustrated in FIGS. 1 through 5 separated from the rest of the mirror toy.
